UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

BEDSPRING ANTISWAY DEVICE.

Application filed May 15, 1922. Serial No. 560,889.

To all whom it may concern:

Be it known that I, DON CARLOS TRAVIS, a citizen of the United States, residing at Kenosha, in the county of Kenosha and State of Wisconsin, have invented certain new and useful Improvements in Bedspring Antisway Devices, of which the following is a specification.

My invention relates to improvements in bed springs and its particular value is in connection with that type of spring in which the resiliency thereof is secured through the use of a series of coiled springs distributed over the supporting area.

The principal objects of the invention are to provide an improved arrangement for bracing the edge or border of the spring against lateral movement, while freely permitting vertical displacement thereof without substantially affecting its comfort or resiliency; to provide a device of the class described which shall be of especial value for springs of the double-deck type and in general, to provide an improved, economical and efficient bed spring of the character referred to.

In the drawings, which illustrate a preferred embodiment of my invention as applied to a coiled spring construction of the double-deck type—

Fig. 1 is a plan view of the device;

Fig. 2, an elevation of same;

Fig. 3 a section taken on the line 3—3 of Fig. 2; and

Fig. 4 is a detail view.

Referring to the drawings, it will be observed that the supporting frame is comprised of a surrounding frame of angle iron, one of the side members of which is indicated at 20. The horizontal flange of said angle iron 20 constitutes a support for the ends of a series of laterals or cross-members 21. The intermediate portions of said cross-members 21 are disposed edgewise or with their major dimensions vertical so as to furnish the desired strength and rigidity, but in order to facilitate connection to the angle iron 20 the ends of said cross-members 21 are turned to an angle of 90 degrees, as indicated at 22, thereby readily permitting said ends to be bent at 23 and 24, in order to bring the outer ends of the cross-members at a higher elevation than the intermediate or edgewise portions. The outer ends 25 of said flatwise portions of the cross-members are rivet-

ed, or otherwise suitably secured, to the horizontal flanges of the angle iron side members 20, and preferably the bends 24 are located some distance from the outer ends of said parts 25 so as to furnish a horizontal shelf or support for the outer rows of springs 26. It will be observed that said springs 26 are of the single-deck type, whereas the intermediate or inner springs 27 are of the double-deck type.

The bottom coils of the outer springs 26 are secured to the portions 25 of the cross-members 21 by means of clips as at 29, said clips having formed therein arched portions as at 30, suitably spaced to fit over and clamp diametrically opposite portions of the said bottom coil.

In springs of this general type, indicated herein, it is customary to equip the outer edge of the "top" of the spring with a surrounding and usually continuous, border wire as at 35, said border wire being suitably united to the outer portions of the top coil of each of the springs 26 in the outer rows.

My improved bracing means is used in connection with said border wire 35 and is supported entirely upon the intermediate or supporting outer angle iron frame 20. The base for said bracing member comprises a downwardly and inwardly extending arm 36 formed of a plate 36 bent into substantially U-shape with the limbs of the U spaced apart a sufficient distance to admit the lower ends of the links 37 and 38. The base wall and lower portions of the side walls of the U-shaped plate 36 project outwardly beneath the vertical flange of the angle iron side members 20, and these side walls project upwardly outside this flange to form a hook 39 (Figs. 2 and 4), firmly positioning the plate. The outwardly turned edge flanges 40 on the plate 36 are extended longitudinally at 41 and these extensions overlie and are riveted to the horizontal flanges of the side members 20 at 42. The base plate thus comprises a pair of angles spaced apart to admit the links and integrally united at their bottom edges.

The links 37 and 38 have their lower ends pivoted on pins or rivets 43 and 44 extending through the oppositely disposed vertical portions of the plate 36. The upper ends of these links 37 and 38 are pivotally connected to pins or rivets 45 and 46 carried by a distance bar 47. This bar 47 is made of a

2
piece of strap metal folded into U-shape with the limbs of the U spaced apart a sufficient distance to admit the upper ends of the links 37 and 38 in substantially the same manner as the plate 36 at their lower ends.

10 The upper end of the bar 47 is flattened out as to its lateral dimension, as shown in Fig. 1, in order to furnish a relatively wide terminal portion, which may be folded around the border wire 35 so as to substantially embrace or enclose the same, as indicated at 49. Preferably the border wire 35 is capable of free rotary movement in the 15 socket thus formed.

Upon inspection of Fig. 2, it will be observed that the inner end of the arm formed by the plate 36 is somewhat lower than the surrounding frame 20, that the link 37 is 20 somewhat longer than the link 38, and that the space between the pivots 43 and 44 is somewhat greater than the spacing of the rivets 45 and 46 carried by the brace bar 47. The dimensions and arrangement of the 25 links and associated parts are such as to provide a system of linkage so organized that the border wire 35 when subjected to external forces is compelled to travel in substantially a straight line perpendicular to the general plane of the bed springs, lateral 30 movement or sway of the border wire being prohibited.

It will be seen from inspection of the 35 dotted line position of said parts that when the linkage is completely collapsed as is the case when the spring is compressed for shipping purposes, the border wire 35 is depressed into a position substantially vertical 40 beneath its ordinary or full line position, and it will also be observed that the brace bar 47 has assumed a substantially horizontal position where it opposes no obstruction to such complete depression of the coils of the spring.

45 Inasmuch as the abuse to which a bed spring of this type is usually subjected, either in service or in shipment, mainly consists of blows or force applied in such a direction as to force the border wire 35 or other parts inwardly, I prefer to construct the linkage and associated supports in the best manner possible to resist such inward movement of the border wire. To this end, when shaping the ends of the vertical flanges 50 of the plate 36 I cut the same slightly on the angle, as indicated at 50, so as to fit up against the vertical flange of the said frame 20. Such expedient furnishes a substantial 55 additional amount of strength and rigidity as against rotary movement of the linkage system around the corner of the angle iron 20 under the influence of blows tending to push the border wire inwardly. Rotary movement in the opposite direction is prevented by the hook 39.

Upward movement of the border wire is limited by the corner 51 of the link 38 engaging against the fold of the base arm. This feature, in combination with the hook 39 is of value when the bed-spring is lifted 70 by the border wire.

The described details of construction and operation, are illustrative of a single phase of my invention, the scope of which should be determined by reference to the appended 75 claims, said claims being construed as broadly as possible consistent with the state of the art.

I claim:

1. In a bed spring, the combination of a 80 bottom support for a series of coiled wire springs, said support comprising a side member and inwardly extending cross-members connected to and depressed below, said side member, an arm connected to and extending 85 inwardly from said side member, a pair of upstanding and upwardly converging links pivotally united to points spaced along said arm, a brace pivotally connecting together the converging upper ends of said links and provided with an upwardly and outwardly 90 extending part and a border wire connected to the upper end of said extension part.

2. In a bed spring, the combination of a 95 bottom support for a series of coiled wire springs, said support comprising a rigid side bar and inwardly extending cross-members connected to, and depressed below, said side bar, an arm rigidly connected to and extending inwardly and downwardly from said side bar, a pair of upstanding links pivotally 100 united at their lower ends to points spaced along said arm, a brace bar pivotally connecting together the upper ends of said links and provided with an upwardly and outwardly 105 extending part and a border wire connected to the upper end of said part.

3. In a bed spring, the combination of a 110 bottom support, comprising a rigid side bar for supporting an outer row of springs, and inwardly extending cross-members connected to, and depressed below, said side bar for supporting inner rows of springs, an arm rigidly connected to and extending inwardly 115 from said side bar, a pair of upstanding and upwardly converging links pivotally united to points spaced along said arm, a brace bar, pivotally connecting together the converging upper ends of said links and provided with an upwardly and outwardly 120 extending part, and a border wire connected to the outer row of springs and to the upper end of said part.

4. In a bed spring, the combination of a 125 bottom support comprising a rigid side bar for supporting an outer row of springs, and inwardly extending cross members connected to, and depressed below, said side bar for supporting inner rows of springs, an arm rigidly connected to and extending in-

wardly from said side bar, a pair of upstanding and upwardly converging links pivotally united to points spaced along said arm, a brace bar, pivotally connecting together the converging upper ends of said links and provided with an upwardly and outwardly extending part, and a border wire connected to the outer row of springs and to the upper end of said part, the brace bar being formed of sheet metal folded to embrace the upper ends of said links, and having its upper end formed to embrace the border wire.

5. In a bed spring, the combination of a bottom support for a series of coiled wire springs, said support comprising a side bar, and inwardly extending cross-members connected to, and depressed below, said side bar, an arm comprising a plate folded into substantially U-shape and rigidly connected to and extending inwardly and downwardly from said side bar, a pair of upstanding and upwardly converging links having their lower ends pivotally united to points spaced along said arm and interposed between the vertical side portions of said plate, a brace bar pivotally connecting together the converging upper ends of said links and provided with an upwardly and outwardly extending part, and a border wire connected to the upper ends of said springs and pivoted to said part.

6. In a bed spring, the combination of a bottom support for a series of coiled wire springs, said support comprising a side member and inwardly extending cross-members connected to and depressed below, said side member, an arm, substantially U-shaped in cross-section, connected to and extending inwardly from said side member, a pair of upstanding and upwardly converging links pivotally united to points spaced along said arm, a brace bar pivotally connecting together the converging upper ends of said links and provided with an upwardly and outwardly extending part and a border wire connected to the upper end of said extension part.

7. In a bed spring, the combination of a bottom support, comprising a rigid side bar for supporting an outer row of springs, and inwardly extending cross-members connected to, and depressed below, said side bar for supporting inner rows of springs, an arm secured to said side bar at vertically spaced points and extending inwardly and downwardly therefrom, a pair of upstanding and

upwardly converging links pivotally united to points spaced along said arm, a brace bar, pivotally connecting together the converging upper ends of said links and provided with an upwardly and outwardly extending part, and a border wire connected to the outer row of springs and to the upper end of said part.

8. In a bed spring, the combination of a bottom support for a series of coiled wire springs, said support comprising a side member, having a vertical and a horizontal flange, and inwardly extending cross-members connected to said side member, an arm secured to and extending inwardly from said side member, a pair of upstanding and upwardly converging links pivotally united to points spaced along said arm, a brace pivotally connecting together the converging upper ends of said links and provided with an upwardly and outwardly extending part and a border wire connected to the upper end of said extension part, said arm being provided with a hook portion interlocking with the edge of the vertical flange.

9. The combination with a spring bed bottom having an upper frame, a lower frame, supporting members carried by said lower frame, and springs on said supporting members, of side thrust supports at the sides of the spring bed bottom, each side thrust support comprising an inclined base piece carried by the lower frame, an inclined supporting piece connected to the upper frame, and linkage connecting the base and supporting piece said linkage causing the supporting piece to swing inwardly when the upper frame is subjected to pressure.

10. In a bed spring, the combination of a bottom support for a series of coiled wire springs, said support comprising a side bar, and inwardly extending cross members connected to, and depressed below, said side bar, an arm comprising a pair of angles rigidly connected to and extending inwardly and downwardly from said side bar, a pair of upstanding and upwardly converging links having their lower ends pivotally united to points spaced along said arm and interposed between said angles, a brace bar pivotally connecting together the converging upper ends of said links and provided with an upwardly and outwardly extending part, and a border wire connected to the upper ends of said springs and pivoted to said part.

DON CARLOS TRAVIS.
